US0D1099144S

(12) **United States Design Patent** (10) **Patent No.:** **US D1,099,144 S**
(45) **Date of Patent:** **** Oct. 21, 2025**

(54) **DISPLAY SCREEN OR PORTION THEREOF SHOWING A GRAPHICAL USER INTERFACE**

(71) Applicant: **Apple Inc.**, Cupertino, CA (US)

(72) Inventor: **Miquel Estany Rodriguez**, San Francisco, CA (US)

(73) Assignee: **Apple Inc.**, Cupertino, CA (US)

(**) Term: **15 Years**

(21) Appl. No.: **29/893,883**

(22) Filed: **Jun. 3, 2023**

(51) **LOC (15) Cl.** **14-04**

(52) **U.S. Cl.**

USPC **D14/486**

(58) **Field of Classification Search**
